THERMOCOUPLE SAFETY PILOT SWITCH

Filed June 17, 1944

Fig. 1

UNITED STATES PATENT OFFICE

2,515,992

THERMOCOUPLE SAFETY PILOT SWITCH

Richard K. Engholdt, Milwaukee, Wis., assignor
to Milwaukee Gas Specialty Company, Milwaukee, Wis., a corporation of Wisconsin

Application June 17, 1944, Serial No. 540,861

9 Claims. (Cl. 200—87)

1

This invention relates, in general, to an electric switch, and has particular relation to a thermocouple safety pilot switch.

The device which I shall describe hereinafter in connection with the drawing is particularly adapted for use with a thermocouple safety control device having an electromagnet connected in circuit with a thermoelectric generator and provided with an armature which is held attracted so long as the thermoelectric generator is heated, for example, by a pilot light for a main burner, and moves to retracted position when the pilot light is extinguished.

One of the main objects of the present invention is to provide an improved form of switch having switch operating means adapted to be pressed to move the armature to attracted position without closing the switch, and, thus, without establishing a supply of fuel for the main burner; the closing of my improved form of switch requiring not only release of the switch operating means, but, also, that the armature be held in attracted position by energization of the electromagnet by the heat, for example, of the pilot flame on the thermocouple.

Another object of the invention is to provide an improved form of switch of the class described of simple construction and composed of few parts; also a device which operates effectively for the purposes set forth.

Another object of the invention is to provide a switch of the class described which in the form selected for illustration requires but one resilient contact carrying member, and does not need a pivoted armature carrying member separate from and in addition to the contact carrying member.

Another object of the invention is to provide, as a part of the switch operating means, an operating member mounted for swinging movement and adapted at one end for actuating the contact carrying member to move the armature to attracted position, the opposite end of the operating member adapted simultaneously to restrain engagement of the contacts until the armature is held in attracted position by the electromagnet and the operating member is released.

Another object of the invention is to provide a device of the character described which is adapted for installation with various types of burner and furnace constructions.

Further objects and advantages of the invention will be apparent from the following detailed description, taken in connection with the accompanying drawing.

In the drawing:

Figure 1 is a schematic view showing one application of a switch embodying the present invention;

Figure 2 is a top plan view of the switch as shown in Figure 1;

2

Figure 3 is a longitudinal sectional view taken on the line 3—3 of Figure 2;

Figure 4 is a transverse sectional view taken on the line 4—4 of Figure 2;

Figure 5 is a fragmentary schematic view showing the contact carrying member in position with the contact carried thereby out of engagement with the cooperating contact and the armature in retracted position;

10 Figure 6 is a view similar to Figure 5, showing the contact carrying arm in position with the contact carried thereby in engagement with the cooperating contact and the armature in attracted position;

15 Figure 7 is a view similar to Figures 5 and 6, showing the operating member actuated to move the armature to attracted position, while restraining engagement of the contact carried by the contact carrying member with the cooperating contact until the armature is held in attracted position by the electromagnet and the operating means is released; and

20 Figure 8 is a fragmentary view similar to Figure 6, showing a modified form of auxiliary spring for the resilient contact carrying member.

25 In Figure 1 of the drawing a gas or other fuel burner of any suitable or preferred type is illustrated at 10. The burner 10 may be the burner of a room or space heater, water heater, floor furnace, gas range, or any other burner. A gas or fuel supply pipe 11 leads to the burner 10 for the delivery of gas or other fuel thereto—for example, through a mixing chamber 12 to which air is admitted in the usual way, as well understood in the art.

30 An electroresponsive valve 13, such as a solenoid or motor valve, is interposed in the fuel supply pipe 11. The valve 13 is shown as comprising a valve body 14 and a hood 15 having any suitable power operated valve actuating means therein. A step-down transformer 16 supplies power for the operation of the valve 13. This transformer comprises a line voltage primary 17 and a low voltage secondary 18. The primary 17 is connected to line wires 19 leading to any suitable source of current or power (not shown). The valve actuating means for the valve 13, the switch of the present invention, which is designated in its entirety at 20, and a thermostat, such as a room thermostat 21, are shown connected in series circuit relation in the secondary circuit 22.

35 For purposes of the present disclosure it may be assumed that the valve 13 is of a character to be actuated to open position by closing of the circuit 22, and to be held in open position to supply fuel to the burner 10 as long as the circuit 22 is closed. The valve 13 may have spring means or other suitable means for actuating the valve 40 to closed position to shut off the supply of fuel

to the burner 10 when the circuit 22 is opened or otherwise disabled.

A pilot burner 23 is placed in juxtaposition to the main burner 10, and provides a pilot light or flame 24 for lighting the main burner. A pipe 25, connected to the fuel supply pipe 11 anterior of the valve 13, or otherwise as desired, supplies fuel for the pilot burner 23.

The particular form of switch selected for illustration comprises a supporting frame 26 having a lug 27 struck to position at right angles to the frame. The U-shaped magnet frame 28 is secured to the lug 27 by screws 29 which may permit adjustment of the magnet frame along the lug 27 for adjustment of the pole ends of the magnet frame toward and away from the armature 30. The shanks of the screws 29 are shown as passing through washers 32 which act as spacers between the lug 27 and the adjacent leg of the magnet frame. The coil 33 is wound around the legs of the magnet frame 28.

A thermocouple, indicated at 35, is placed in position so that the hot junction 36 thereof will be heated by the pilot flame 24 as long as the pilot flame is burning. While the thermocouple and leads therefor are shown as similar to the thermocouple and leads more fully disclosed in Oscar J. Leins Patent No. 2,126,564, issued August 9, 1938, it is to be understood that the thermocouple and its leads may be of any other suitable or preferred form within the scope of the present invention.

For the purpose of the present description, suffice it to state that the particular thermocouple selected for illustration comprises an outer tubular metallic thermocouple element and an inner metallic thermocouple element of different thermoelectric characteristics. The thermocouple elements are joined to form the hot junction 36. An outer tubular lead conductor 37 is connected to the outer thermocouple element, for example, through a sleeve 38. The inner lead conductor 39, enclosed by and insulated from the outer tubular lead conductor 37, is connected to the inner thermocouple element. The inner lead conductor 39 is connected in circuit with one side of the coil 33, and the outer lead conductor 37 is connected in circuit with the opposite side of the coil 33, for example, through a conductor 40, as shown in Figure 1.

The resilient contact carrying member 42 is fixedly secured or anchored at one end to the frame 26, for example, by a rivet 43. The member 42 constitutes an electric conductor for the circuit 22, one of the conductors of the circuit 22 being connected, for example, to the fixedly anchored end of the member 42, and a continuation of such conductor of the circuit 22 being connected to a lug 44 on a conducting strip 45 to which a stationary contact 46 is secured. The conducting strip 45 is positioned between a pair of insulating strips 47, and the contact 48, on the outer end of the contact carrying member 42, moves into and out of contact with the contact 46 and between the inner insulating strip 47 and a third insulating strip 49. The insulating strips 47 and 49 and conducting strip 45 are secured together and to the adjacent end of the frame 26, for example, by rivets 50, or otherwise as desired. The armature 30 is also fixedly secured to the contact carrying member 42, for example, by soldering, or otherwise as desired.

The resilient contact carrying member 42 tends, by reason of its own resilience, toward a first

position engaging the insulating strip 49 which serves as a stop for limiting movement of the free end of the member 42 in this direction. A pin 52 on the contact carrying member 42 operates in an opening in the strip 49 to guide the free end of the member 42 and prevent lateral displacement of the contact 48 on the member 42 relative to the contact 46.

In the particular form of device illustrated in Figures 1 through 7 of the drawing, the contact carrying outer end of the resilient member 42 is shown as terminating in an integral laterally elongated part having integral auxiliary spring strips 55 parallel with the member 42, and with one of the auxiliary spring strips 55 on each of the opposite sides of the member 42. These auxiliary spring strips 55 are secured at 56 to lugs 57 integral with the frame 26, and the auxiliary spring strips 55 are bowed as shown in Figures 3, 5, 6, and 7 to present an additional or auxiliary force which tends to move the contact carrying member 42 toward the insulating strip or stop 49 with the contact 48 out of engagement with the contact 46.

An operating member 60 is mounted at 61 for swinging or pivotal movement, and is adapted at one end 62 to engage and move the contact carrying member 42 in a direction to move the armature 30 from its retracted position shown in Figure 5 to its attracted position shown in Figures 6 and 7. The opposite end of the member 60 has a portion 63 which extends around the adjacent end of the contact carrying member 42 to engage this member 42, at 64, simultaneously to restrain engagement of the contact 48, carried by said member, with the contact 46 as the member 60 is swung in a clockwise direction about its pivot from the position shown in Figure 5 to the position shown in Figure 7, and until the armature 30 is held in attracted position by the electromagnet and the operating member is released.

A push button 65 is provided for swinging the member 60 about its pivot 61, from the position shown in Figure 5 to the position shown in Figure 7. The button 65 extends out through an opening in the adjacent member 68 for engagement by the hand or finger, as shown in Figure 7. A tension spring, shown more or less schematically at 70, may be provided for holding the adjacent end of the member 60 yieldingly against the inner end of the button 65 and for holding the button 65 in its outwardly projected position, as shown in Figures 5 and 6, and for returning the button to this position.

In the modification illustrated fragmentarily in Figure 8 I have shown an auxiliary tension spring 72, instead of the auxiliary spring portions 55, for presenting the additional force which tends to move the contact carrying end of the contact carrying member toward the insulating strip or stop 49, with the contact 48 out of engagement with the contact 46.

To start the operation of the system shown in the drawing, the following sequence is followed:

The button 65 is engaged with the hand or finger and pressed inwardly, and by its engagement with the adjacent end of the operating member 60 swings this member 60 clockwise about its pivot 61 from the position shown in Figure 5 to the position shown in Figure 7. The adjacent end 62 of the member 60 engages the resilient contact carrying member 42, and moves the portion of the member 42 adjacent the armature 30 toward the electromagnet and the

armature 30 to attracted position. The opposite end of the member 60, by its engagement with the opposite side of the contact carrying member 42 at 64 (Figure 7), simultaneously holds the contact carrying end of the resilient member 42 against movement toward the contact 46, thereby restraining engagement of the contact 48 with the contact 46 until the armature 30 is held in attracted position by the electromagnet and the operating button 65 is released.

Upon ignition of the pilot burner 23, the pilot flame 24, by heating the hot junction 36 of the thermocouple 35, energizes the electromagnet sufficiently to hold the armature 30 in attracted position. When the button 65 is released with the armature 30 held in attracted position by the electromagnet, the spring 70 returns the button to its outwardly projected position and releases engagement of the member 60 with the member 42, at 64. The contact carrying end of the contact carrying member 42, having been held under tension with the contact 48 out of engagement with the contact 46, snaps into position with its contact 48 in contact with the contact 46. Assuming that the circuit 22 is also closed at the thermostat 21, the valve 13 is opened by completion of the circuit 22 for the supply of fuel to the main burner 10, which is then ignited by the pilot flame 24.

From the foregoing it will be apparent that the switch 20 closes the circuit 22 not by the inward movement of the button 65 or by the armature resetting operation, but only if and after the armature 30 is reset and held in attracted position by the electromagnet and the button 65 is released. The closing of the circuit 22 and opening of the valve 13 for the supply of fuel to the main burner is thus prevented except when the pilot burner is ignited so that it will ignite the fuel which is delivered to the main burner.

If the heat of the pilot flame on the thermocouple has not generated sufficient E. M. F. to hold the armature 30 in attracted position, the resilient contact carrying member 42 will, by reason of its own resilience and/or the resilience of the auxiliary spring means, where such auxiliary spring means is employed, return the member 42 to position, with the armature 30 retracted and the contact 48 out of engagement with the contact 46, the switch remaining open and the valve 13 remaining closed.

If, after the parts are set, as shown in Figure 6, and the pilot burner is lighted to hold the parts in the positions shown in this figure, the pilot flame is extinguished, the armature is released. The resilient contact carrying arm 42 then moves from the position shown in Figure 6 to the position shown in Figure 5. This moves the armature 30 to retracted position, and separates the contact 48 from the contact 46, thus opening the circuit 22 and closing the valve 13 to shut off the supply of fuel to the main burner.

The embodiment of the invention shown in the drawing is for illustrative purposes only and it is to be expressly understood that the drawing and the accompanying specification are not to be construed as a definition of the limits or scope of the invention, reference being had to the appended claims for that purpose.

I claim:

1. In a switch of the class described, in combination, a fixed contact, a resilient contact carrying member having a movable contact thereon and tending by its own resilience to move the con-

tact thereon out of contact with said fixed contact, an armature on said contact carrying member, an electromagnet for said armature, an operating member operable to move only the part

5 of said contact carrying member adjacent to the armature thereon in a direction to move said armature to attracted position relative to said electromagnet, and means on said operating member and cooperating with said contact carrying member to restrain accompanying movement of the part of said contact carrying member adjacent to the contact thereon whereby to prevent contact of the contact on said contact carrying member with said fixed contact until

15 said armature is held in attracted position by said electromagnet and said operating member is released.

2. A switch according to claim 1 wherein the contact carrying member is in the form of a re-

20 siliert strip anchored at the end opposite the end having the movable contact thereon to a supporting frame and wherein the end of said resilient strip having the movable contact thereon has a laterally elongated part provided with auxiliary spring strips parallel with said contact carrying strip, each of said auxiliary strips being integral at one end with said contact carrying strip and secured at their opposite ends to said supporting frame, said auxiliary strips 25 presenting additional force which tends to move the movable contact on said contact carrying strip out of contact with said fixed contact.

3. A switch according to claim 1 wherein the operating member is disposed on one side of said

30 contact carrying member and the means on said operating member for restraining accompanying movement of the part of said contact carrying member adjacent to the contact thereon cooperates with the opposite side of said contact

40 carrying member.

4. A switch according to claim 1 wherein the operating member is pivoted between its ends for engagement on one side of said pivot with the contact carrying strip in proximity to the

45 position of the armature thereon.

5. A switch according to claim 1 wherein the operating member is pivoted between its ends for engagement on one side of said pivot, with the contact carrying strip in proximity to the position

50 of the armature thereon and wherein there is a push button cooperable with said contact carrying strip on the side of its pivot at which said armature is disposed.

6. A switch according to claim 1 wherein the operating member is pivoted between its ends for engagement on one side of said pivot, with the contact carrying strip in proximity to the position

55 of the armature thereon and wherein there is a push button cooperable with said contact carrying strip on the side of its pivot at which said armature is disposed.

60 7. In a switch of the class described, in combination, a resilient contact carrying member tending by its own resilience to move to a first circuit controlling position, a contact on one part of said contact carrying member, an armature on another part of said contact carrying member, an electromagnet for said armature, and means operable to move only the part of said contact carrying member adjacent to the armature thereon in a direction to move said armature to at-

65 tracted positions relative to said electromagnet.

70 8. In a switch of the class described, in combination, a fixed contact, a resilient contact carrying member having a movable contact thereon and tending by its own resilience to move the con-

75 tact thereon out of contact with said fixed contact, an armature on said contact carrying member, an electromagnet for said armature, an operating member operable to move only the part of said contact carrying member adjacent to the armature thereon in a direction to move said armature to at-

and for, at the same time, restraining the part of said contact carrying member adjacent to the contact thereon against accompanying movement.

8. A switch according to claim 7 wherein the resilient contact carrying member comprises a spring strip tending by its own resilience to move to a first circuit controlling position when the electromagnet is deenergized, said spring strip having a portion thereof on which the contact is carried tending to a second circuit controlling position when the electromagnet is energized and the armature on said contact carrying member is held attracted to the electromagnet.

9. In a switch of the class described, in combination, a resilient contact carrying member, a contact on one part of said contact carrying member, an armature on another part of said contact carrying member, an electromagnet for holding said armature in attracted position, said resilient contact carrying member tending by its own resilience to move to a first circuit controlling position when the electromagnet is deenergized, the contact carrying portion of said resilient contact carrying member tending to move to a second circuit controlling position when the armature is held attracted to the electromagnet, operating means operable to move the armature carrying part of said resilient contact carrying member to position in which the armature is held attracted by said electromagnet, and means

5
